DESIGN FOR AN END PLATE FOR BICYCLE PEDALS

Harry Golden, New York, N. Y.

Application June 8, 1944, Serial No. 113,918

Term of patent 14 years

(Cl. D90—14)

To all whom it may concern:

Be it known that I, Harry Golden, a citizen of the United States, residing at New York, county of New York and State of New York, have invented a new, original, and ornamental Design for End Plate for Bicycle Pedals, of which the following is a specification, reference being had to the accompanying drawing, forming a part thereof.

Figure 1 is a front elevational view of an end plate for bicycle pedals embodying my new design; and

Figure 2 is a top plan view thereof.

I claim:

The ornamental design for an end plate for bicycle pedals, as shown.

HARRY GOLDEN.
